[57] CLAIM

The ornamental design for accessory support attachment for a worktable, as shown and described.

DESCRIPTION

FIG. 1 is a perspective view of an accessory support attachment for a worktable, showing my new design;

FIG. 2 is a front elevational view thereof;

FIG. 3 is a rear elevational view thereof;

FIG. 4 is a side elevational view, the opposite side being a mirror image thereof;

FIG. 5 is a top plan view thereof, the bottom plan being identical thereto;

FIG. 6 is a perspective view of an accessory support attachment for a worktable, showing a second embodiment of my new design;

FIG. 7 is a front elevational view thereof;

FIG. 8 is a rear elevational view thereof;

FIG. 9 is a side elevational view of the second embodiment, the opposite side being identical thereto; and

FIG. 10 is a top plan view of the second embodiment, the bottom plan being identical thereto.

The broken lines in FIGS. 1 and 6 have been shown for illustrative purposes only.

FIG. 2

FIG. 4

FIG. 8

FIG. 10
